ATTORNEYS

UNITED STATES PATENT OFFICE.

RICHARD G. LEDIG, OF PHILADELPHIA, PENNSYLVANIA, ASSIGNOR TO A. MECKY COMPANY, OF PHILADELPHIA, PENNSYLVANIA, A CORPORATION OF PENNSYLVANIA.

MUFFLE.

1,358,220.

Specification of Letters Patent. Patented Nov. 9, 1920.

Application filed November 15, 1919. Serial No. 338,294.

To all whom it may concern:

Be it known that I, RICHARD G. LEDIG, a citizen of the United States, residing in the city and county of Philadelphia, State of Pennsylvania, have invented a new and useful Muffle, of which the following is a specification.

My invention relates to the class of muffles for electric heaters or other purposes, and it 10 consists of a muffle adapted to become red hot its extreme length, especially from the edges of its ends, and so the volume of heat from the muffle is increased to that extent while the black end portions of the muffle 15 heretofore occasioned are avoided.

It further consists of details of construction as will be hereinafter described.

The invention is satisfactorily illustrated in the accompanying drawing, but the important instrumentalities thereof may be varied, and so it is to be understood that the invention is not limited to the specific details shown and described, as long as they are within the spirit or scope of the claims.

25 Figure 1 represents a side elevation of a muffle embodying my invention.

Fig. 2 represents a central longitudinal section on line 2—2 Fig. 1.

Fig. 3 represents an end view thereof.

30 Similar numerals of reference indicate corresponding parts in the figures.

Referring to the drawings,

1 designates the body of a muffle, the same being of cylindrical or other conventional 35 shape and composed of porcelain or other suitable material, and 2 designates the resistance wire or thread wrapped or wound spirally thereon on the exterior surface thereof, it being noticed that said body is 40 covered by said thread to the extreme edges of the ends of the former, whereby the surface of the body is enveloped completely from edge to edge of the ends thereof, leaving, however, small members thereof uncovered, as will be hereinafter referred to.

The interior wall of the body 1 at the end portions thereof is tapering as at 3 from near the edges thereof to said edges, as most plainly shown in Fig. 2.

45 On the opposite edges of the body are the lips 4 which project laterally therefrom as integral portions thereof and they have perforations or eyes 5 therein, it being noticed

that the thread 2 extends to said lips which is the only part of the body uncovered by the 55 same.

In each eye 5 is passed the adjacent portion of the soft iron binding wire 6 to which the adjacent end of the thread 2 is connected by twisting or other suitable means, thus 60 providing means for supporting the muffle at its place of service, it being evident that the wire 6 and the thread 2 are carried on to the point of electric conductivity.

It will be seen that when the thread 2, the 65 resistance wire, is electrically energized, as the muffle is covered by the same its entire length from edge to edge (excepting, however, the short distance of the exterior of the lips 3), it will become red hot and so 70 produce increased heat to that extent, thus overcoming the tendency of the end portions of the body becoming black, as heretofore occasioned.

The body is hollow as well known, but the 75 tapering portions of the inner wall thereof serve to thin the material at said portions, hence the latter will become more easily red-hot, it being evident that owing to said tapering surfaces the energized wire has less 80 refractory material of the body to heat, white heat, at the ends of the body than it has in the middle of the latter.

Having thus described my invention what I claim as new and desire to secure by Letters Patent, is:—

1. In a muffle, a body and an electric conducting thread thereover, said body having the extreme edges of its ends covered by said thread.

2. A muffle consisting of a hollow body, and an electric-conducting thread thereon, said thread extending over said body from the extreme edges of the ends thereof, the interior surface of the end portions of said body being tapered outward to said edges.

3. A muffle comprising a hollow body member, an electric-conducting thread thereon, said hollow body member having a projection at each end thereof for the binding of the conductor to said body member with a binding wire.

RICHARD G. LEDIG.
